(57) **CLAIM**

We claim the ornamental design for a display screen or portion thereof with transitional graphical user interface, as shown and described.

DESCRIPTION

FIG. 1 is a front view of a first image of a display screen or portion thereof with transitional graphical user interface showing our new design;

FIG. 2 is a second image thereof;

FIG. 3 is a third image thereof;

FIG. 4 is an enlarged view of the claimed portion of FIG. 1, for clarity of illustration;

FIG. 5 is an enlarged view of the claimed portion of FIG. 2, for clarity of illustration; and,

FIG. 6 is an enlarged view of the claimed portion of FIG. 3, for clarity of illustration.

The appearance of the transitional image sequentially transitions between the images shown in FIGS. 1-3. The process or period in which one image transitions to another image forms no part of the claimed design.

The outermost broken lines in the figures depict a display screen or portion thereof and form no part of the claimed
